(57) **CLAIM**

I claim the ornamental design for the transparent adult bib with multiple pockets, as shown and described.

DESCRIPTION

FIG. 1 is a front view of the transparent adult bib with multiple pockets.

FIG. 2 is a rear view of the claimed design.

FIG. 3 is a left side view of the claimed design.

FIG. 4 is a top view of the claimed design.

FIG. 5 is a bottom view of the claimed design; and,

FIG. 6 is a perspective view of the claimed design.

In FIGS. 1-6, the lines connecting the clip features are shown with a symbolic break in its length. The appearance of any portion of the article between the break lines forms no part of the claimed design.
